UNITED STATES PATENT OFFICE.

ELLIOTT D. FISHER, OF FRANKLINVILLE, NEW YORK.

STOVE-PIPE-FITTING TOOL.

SPECIFICATION forming part of Letters Patent No. 450,910, dated April 21, 1891.

Application filed August 9, 1890. Serial No. 361,598. (No model.)

To all whom it may concern:

Be it known that I, ELLIOTT D. FISHER, of Franklinville, in the county of Cattaraugus and State of New York, have invented a new 5 and useful Stove-Pipe-Fitting Tool, of which the following is a full, clear, and exact description.

The object of this invention is to provide in one compact and simple implement a ready 10 and efficient means for expanding one end of a stove-pipe joint and correspondingly contracting the end of a similar pipe-joint to adapt them for a sliding connection.

To this end my invention consists in the 15 peculiar construction of the implement, as is hereinafter described and claimed.

Reference is to be had to the accompanying drawings, forming a part of this specification, in which similar letters of reference indicate 20 corresponding parts in all the figures.

Figure 1 represents the preferred form of the device and its method of application to expand and contract the ends of stove-pipe sections. Fig. 2 is a slightly-changed form 25 for the device. Fig. 3 is another modification, and Fig. 4 is a view of an ordinary cone-frustum on which my construction is an improvement.

In all the figures the device presented in 30 modified forms has the main essential feature shown, which consists in making the implement tubular and cone-frustum in form.

In Fig. 1, as presented, the implement consists, essentially, of a frustum A of a hollow 35 cone having a short annular sloping shoulder a at a point which is near the longitudinal center of the implement. From the shoulder a to the smaller end b a regular taper is given to the body A, and upon this terminal end an 40 inward-contracting curvature of the material is produced, thus adapting this end of the tool to enter the end of a stove-pipe section B and expand the same, if a revolute motion and longitudinal pressure is applied to the tool.

45 From the shoulder a toward the opposite terminal end c of the tool A the diameter is regularly increased, and at the edge is outwardly curved into a slightly-bell-shaped entrance, wherein the end of a stove-pipe section C that 50 is equal in diameter to the section B may be introduced, and by a proper manipulation of the tool be slightly crimped, so as to contract

the diameter of this pipe end portion c' and render it tapering toward the shoulder a, which, when internally engaged by the end c' of the pipe-section C, will give the same a short inward bend. In a similar manner the end a' of the pipe-section B, if made to impinge on the revolubly-moving shoulder a on its exterior surface, will be slightly bent outward, and thus adapted to receive the tapered end of the other pipe-section C.

In Fig. 2 the same form is given the tool A, except that the end c is not flared, the operation of the tool is the same, and if proper 65 proportions are maintained between the pipe to be fitted and the diameter of the tool efficiency in operation will result from use of this slightly-altered form of the device.

In Fig. 3 the device has its ends left uncurved, there being the offset shoulder a, produced on the conical body of the tool, which will remove all irregularities on the edge of the expanded pipe-section and turn in the edge of the crimped section, so that these sections may be readily slid together until a tight 75 joint is secured.

The tool shown in Fig. 4 cannot be as readily inserted into or over the pipe ends and produces flares or contracts said ends to a much 80 greater length than is necessary and consistent with economy, for with such a long flare a much longer portion of the opposing pipe-section must be inserted therein than is necessary where only the extreme end edges are 85 flared or contracted, as the case may be, by means of the short sloping annular shoulder a of my implement. Moreover, the joined ends of pipes treated by my implement will lie almost in the planes of their remaining portions, and a much neater joint will thus be 90 effected.

It is to be understood that the several sections of a stove-pipe to be joined are each expanded at one end and crimped at the opposite end, so as to adapt them for a proper connection and formation of an extended line of pipe.

Having thus fully described my invention, I claim as new and desire to secure by Letters 100 Patent—

1. A stove-pipe-fitting tool comprised of a hollow conical body having an annular shoulder formed on its longitudinal center produc-

ing tapering integral portions of different diameters at their point of junction, substantially as set forth.

2. A stove-pipe-fitting tool comprised of a hollow conical body having an annular slightly-sloping shoulder formed on it near its center of length and its smaller terminal end curved inwardly, substantially as set forth.

3. A stove-pipe-fitting tool comprised of a hollow conical body having an annular slight-

ly-sloping shoulder formed on it near its center of length, an inward curvature produced on the edge of the small end, and a flaring mouth on the larger end of the tool, substantially as set forth.

ELLIOTT D. FISHER.
